UNITED STATES PATENT OFFICE.

HERMANN C. BERNNER, OF PROVIDENCE, RHODE ISLAND.

HAIR-DRYING APPARATUS.

SPECIFICATION forming part of Letters Patent No. 642,287, dated January 30, 1900.

Application filed July 28, 1899. Serial No. 725,373. (No model.)

To all whom it may concern:

Be it known that I, HERMANN C. BERNNER, of Providence, in the county of Providence and State of Rhode Island, have invented a new and useful Improvement in Hair-Drying Apparatus; and I hereby declare that the following is a full, clear, and exact description of the same, reference being had to the accompanying drawings, forming part of this specification.

This invention has reference to improvements in the construction of an apparatus for heating air and forcing the heated air through hair to remove the moisture.

15 The invention consists in the peculiar and novel construction and the combination of the parts whereby atmospheric air is heated and a current of heated air may be directed, as will be more fully set forth hereinafter.

20 Figure 1 is a side view of my improved apparatus. Fig. 2 is a view of one end, and Fig. 3 a view of the opposite end, of the same. Fig. 4 is a vertical longitudinal sectional view through the center of the apparatus. Fig. 5 is a transverse sectional view through the air-heating chamber, showing the burner and the deflector-plate.

Similar marks of reference indicate corresponding parts in all the figures.

30 In the drawings, A indicates the table forming the supporting-base for the apparatus. The legs of the table are preferably supplied with casters, so that the apparatus may be readily moved.

35 On the table A are supported the chambers B, C, and D. The chamber B contains the electric motor b' and has the door b², sliding in the ways b³ b⁴, and b⁵ the conductor-wires connected with the electric motor.

40 In practice I find it best to use the chamber B; but it may be omitted and the motor exposed to view. While the electric motor is convenient in use and preferable, any other suitable motor may be used. The transverse 45 sectional form of the chamber B is that of the inverted capital letter U.

The chamber C is of cylindrical form. The end disk c' divides it from the chamber B. The shaft b⁵ of the electric motor b' extends 50 through the end disk c' and connects with the fan-blower b⁶, which is driven by the motor. The disk c², closing the opposite end of the

chamber C, is perforated with the openings c³ c⁴.

On one side of the peripheral casing of the 55 chamber C the hood c⁴ extends tangentially from and covers an opening in the casing and connects with the funnel c⁵, to which the flexible tube c⁶ is secured, connecting at the upper end with the nozzle c⁷, provided with the 60 handhold c⁸. The opening in the peripheral casing of the chamber C is on the side on which the blades of the fan-blower b⁶ move upward to drive the air through the tube c⁶.

The chamber D has one side secured to the 65 end disk c² of the chamber C, leaving the openings c³ c⁴ to form passages for the air from the chamber D to the chamber C. The chamber D is provided with the large burner d', having the by-pass d² to form a permanent torch 70 for lighting the burner d'. Gas is supplied through the pipe d³ to the burner d'. A valve connected with the arm d⁴ is operated to control the gas by the rods d⁵ d⁶, connected with the arm d⁴. One or two rods may be used. 75 When two rods are used, the arm d⁴ is counterbalanced by the two rods secured to the opposite ends of the arm to hold the valve in the desired position. When one rod d⁵ is to be used, the arm may be counterbalanced by 80 a weight secured to the arm d⁴ at the end opposite to the end on which the valve-operating rod d⁶ is secured.

The chamber D is preferably provided at one side with the sliding door d⁷ to give access to the burner and at the end with the perforated sliding door, through the perforations of which the air is admitted to the chamber D. If desired, the door d⁷ may be omitted and access may be had to the burner d' 90 through the door d⁸.

To secure the uniform heating of the air, it is desirable to supply it evenly in small streams through the perforations in the door d⁸ and bring it into contact with the heated 95 surfaces before it is drawn by the fan into the chamber C.

To secure the best result, I place into the chamber D, between the burner and the openings c³ c⁴ in the end disk c², the deflector-plate, 100 bent at a right angle at its upper end and perforated at its upper portion with the openings d¹⁰ d¹¹.

In using the apparatus the burner d' is first

lighted. As the burner is a large Argand heating-burner, the interior and the walls of the chamber D are quickly heated. The fan-blower b^6 is now started by setting the motor 5 in operation. The revolution of the fan-blower forces the air tangentially out of the chamber C through the hood c^4 , covering the opening in the side of the chamber, and through the tube c^6 , to be discharged from the 10 nozzle c^7 . The partial vacuum formed in the chamber C is supplied by air passing through the perforations in the door d^8 coming in contact with the burner and the heated surfaces 15 of the walls of the chamber C and the deflector-plate d^9 . Some of the heated air passes through the openings $d^{10} d^{10}$ in the deflector-plate; but the bulk of the heated air rising by its lightness passes over the deflector-plate d^9 and comes in contact with the heated 20 surface of the arch d^{12} , forming the upper part of the chamber D, to pass through the openings $c^8 c^8$ into the chamber C, and is driven by the fan-blower out of the end of the nozzle c^7 .

25 The operative holds with one hand the hair that has been washed, and holding with the other hand the nozzle c^7 by the handhold c^8 directs the stream of heated air on and through the hair until it has reached the desired degree 30 of dryness.

Having thus described my invention, I claim as new and desire to secure by Letters Patent—

1. In an apparatus for drying hair, in combination, a table forming the support of the 35 apparatus, a heating-chamber, the arched top

of the heating-chamber, a perforated door closing normally the end of the heating-chamber below the lowest point of the arched top of the chamber, a burner in the heating-chamber, a perforated deflector-plate, a fan-chamber, means for operating the fan, openings connecting the heating-chamber with the fan-chamber, a tangential outlet from the fan-chamber, a flexible tube connected with the 40 tangential outlet, and a nozzle at the end of the flexible tube, whereby the heated air may be forced on and through the hair, as described.

2. In an apparatus for drying hair, the combination with the table A and the chambers B, C and D supported on the table, of the motor b' , the fan b^6 connected with and driven by the motor, the hood c^4 inclosing the tangential outlet-opening in the peripheral wall 55 of the chamber C, the flexible tube c^6 , the nozzle c^7 provided with a handhold, the door b^2 in the chamber B, the door d^7 and the perforated door d^8 in the chamber D, the burner d^9 and means for controlling the same, and 60 openings connecting the chamber C with the chamber D, whereby the air heated in the chamber D is discharged from the nozzle and may be directed by the operative, as described.

In witness whereof I have hereunto set my hand.

HERMANN C. BERNNER.
